UNITED STATES PATENT OFFICE.

HARRY H. HANCOCK, OF SWAMPSCOTT, MASSACHUSETTS.

RECEPTACLE.

1,136,421.

Specification of Letters Patent. Patented Apr. 20, 1915.

Application filed December 28, 1912. Serial No. 789,000.

To all whom it may concern:

Be it known that I, HARRY H. HANCOCK, a citizen of the United States, and resident of Swampscott, county of Essex, State of Massachusetts, have invented an Improvement in 5 Receptacles, of which the following description, in connection with the accompanying drawings, is a specification, like letters on the drawings representing like parts.

10 My invention relates to receptacles and more particularly to receptacles for use in holding, storing and preserving printing rolls.

The types of printing rolls at present in 15 general use are (excepting the metal core or spindle) composed of perishable material, being much softer and more destructible than rubber though resembling rubber in resiliency. Such rolls are generally made of 20 a composition comprising glue, glycerin and syrup, and besides being greatly affected by changing degrees of moisture in the weather, they are very liable to be damaged by mice and other vermin. These rolls are 25 ordinarily left lying horizontally in open racks (when not in use) supported by the spindles at either end, but a great objection to this practice is that the material of the rolls being soft and mobile, tends to warp, 30 sag and flow downwardly, thereby impairing the rotundity of the roll and often rendering the roll so uneven as to be unfit for use, as well as drying out in the open air of the printing room.

35 It is an object of my invention to provide a receptacle which shall be capable of holding and preserving printing rolls and maintaining them in proper consistency and sustaining them in such a manner as to protect 40 all tendency to impair the rotundity of the roll, and to prolong the life and the use of such rolls.

It is also an object of the invention to provide a portable receptacle which will be substantially fire proof and vermin proof, which will be economical to build, convenient to use, adjustable in certain dimensions, which will occupy but little space, and which may be utilized to contain other articles in addition 50 to the printing rolls.

Other features of the invention and details of construction will be hereinafter pointed out and claimed.

55 The accompanying drawings illustrate a preferred embodiment of the invention, wherein—

Figure 1 is a longitudinal sectional view; Fig. 2 is a plan view on the line 2—2 of Fig. 1; Fig. 3 is a plan view on the line 3—3 of Fig. 1; Fig. 4 illustrates a detail on an enlarged scale.

Referring to the drawings, 1 indicates a base for the receptacle, which is preferably formed of metal with legs 2 and has a central socket in which a shaft 4 is fitted. A 65 cylindrical receptacle comprising sides 6, a top 8, and the bottom plate 9, having a central sleeve 10, is arranged to be supported by the shaft 4 and base 1. Preferably, the weight of the receptacle is sustained on the 70 upper end of the shaft 4, said end being beveled and contacting with a bearing member 12 fitted in the sleeve 10 at a proper point to rest on the beveled end of the shaft, so that but comparatively slight, if any, weight is 75 borne by the base 1 where the bottom 9 may contact with it. The portion 9 is formed hollow to contain moistening or preserving liquid, with suitable reinforcing webs 14 therein and with openings 15 in the upper 80 part. A plurality of depressions 16 are also provided, each of appropriate size, to receive the lower end of the spindle of a printing roll. In the top 8 are arranged a number of apertures through which holders 18 are fitted 85 to slide easily. Each holder comprises a head 20, which limits its downward movement by catching on the top 8, and a hollow tube-like stem, which is adapted to fit over the upper end of a printing roll spindle, to 90 hold a printing roll, as clearly shown in Fig. 1. These spindles may be provided with a collar 22, for the purpose of contacting with the lower end of the holder 18 and prevent its resting upon the soft composition of the 95 printing rolls.

It will be noted that the entire receptacle is arranged to be revolving, practically swinging by the member 12 on the end of the shaft 4. In order to steady such revolving action a loose washer 7 is placed over the shaft 4, and as said washer rests on the base 1 it is interposed between the shaft 4 and the lower end of the sleeve 10. A passage 13 is provided through the member 12, 100 in order to permit of oiling the bearing between the member 12 and the shaft 4. The cylindrical sides 6 of the receptacle are preferably formed as doors, three doors being shown in Fig. 2, each door being suitably 105 hinged in any well known manner as by pins 25 and each having a conveniently

placed handle and locking catch as indicated at 26.

Fig. 4 indicates a drying cartridge 28, which may be filled with absorbing material, to absorb the moisture within the receptacle, if, as often happens, the air is so moist that the liquid should be removed from the hollow bottom 9 or prevented from evaporation into the receptacle. The drying cartridges 10 28 are so shaped that they may be placed in the openings 15 and thereby prevent the rolls from becoming too moist.

Besides the advantages possessed by my improved cabinet holder of being substantially dust-proof, vermin-proof and preserving the rolls contained therein, as well as occupying but a small space and affording a convenient receptacle and worktable on the top, my cabinet may be most economically 20 constructed. By casting the base 1 and also by casting the bottom 9 of the receptacle suitably cored, a very economical construction is produced. Also the entire structure is made of stock material, and only the top 25 of the shaft 4 and the corresponding surface of the bearing member 12 need be machined. As the expense of such devices is of very material importance from a practical standpoint, these features in the device embodying my invention are of special importance. 30

Having described my invention, what I claim as new and desire to secure by Letters Patent is:

1. A cabinet to contain printing rolls comprising a base, a shaft extending upwardly from the base, a receptacle arranged to revolve on said shaft, having a central sleeve with a pivoted bearing therein for said shaft, the receptacle having a cored bottom 35 portion to contain liquid, means to engage the lower end of a printing roll spindle on

the bottom portion of said shaft, a top having perforations, and adjustable holders arranged to slide through said perforations to engage the upper end of said printing roll 45 spindle and thereby hold it in vertical position.

2. A cabinet to contain printing rolls, comprising a base, a shaft extending upwardly from said base, a receptacle arranged to revolve on said base, having a central sleeve engaging said shaft formed with a bearing member intermediate its ends, constructed to engage the end of said shaft, means in the bottom portion of said receptacle to engage one end of a printing roll 50 spindle and adjustable means, slidable through the top of said receptacle, to engage the other end of said printing roll spindle, substantially as described. 55

3. A rotatable cabinet to contain printing rolls, comprising a stationary cored base adapted to contain liquid to preserve said rolls, the bottom of said cabinet being a cover for said liquid, means to hold printing 60 rolls within said cabinet, comprising depressions in the top of said base cover, perforations through said cover to admit of moisture passing from the base to the rolls, a top for the cabinet having perforations therein, and 65 hollow tubular members arranged to slide through said perforations to engage the upper end of the printing roll spindles to hold the same in vertical position.

In testimony whereof, I have signed my 70 name to this specification, in the presence of two subscribing witnesses.

HARRY H. HANCOCK.
